TUNED ELECTRIC CIRCUITS

Evelyn Stewart Lansdowne Beale, Chelsea,
London, England, assignor to International
Standard Electric Corporation, New York, N. Y.

Application July 1, 1938, Serial No. 216,919
In Great Britain July 27, 1937

12 Claims. (Cl. 250—36)

This invention relates to an electric circuit responsive to low frequencies and which may be adapted to operate either as a frequency selective circuit for low frequencies or as a circuit capable of generating oscillations of low frequency.

It is well known that in circuits for passing low frequencies difficulties are usually encountered over the design of the inductances which tend to become heavy and bulky if they are to have a sufficiently high ratio of reactance to resistance to be useful. It is therefore an object of the present invention to overcome the above disadvantages.

15 The underlying idea of the present invention is to provide a low frequency responsive device including what may be called a fundamental circuit capable of operating in a manner similar to a tuned circuit and responsive to low frequencies, the said fundamental circuit containing resistances and capacities but no inductances.

According to a feature of the present invention there is provided an amplifier comprising a fundamental circuit containing no inductances but resistances and capacities so arranged as to form a low pass section and a high pass section, the low pass section being in the amplifier circuit and the high pass section being in a feed back circuit, the net gain of the amplifier being 25 adjusted so that the minimum of the resultant attenuation curve of the two sections of the fundamental circuit comes close to but not quite up to the level of zero attenuation, whereby the fundamental circuit operates in a manner analogous to a tuned circuit responsive to the "resonant" frequency.

The invention also includes an oscillator for generating low frequency oscillations, characterized in this, that the oscillator comprises a fundamental circuit containing no inductances but resistances and capacities so arranged as to form a high pass section forming a feed back circuit and a low pass section forming part of the amplifier circuit, the net gain of the amplifier 40 being increased until the attenuation of the fundamental circuit is substantially zero whereby the circuit is rendered unstable and starts to oscillate at the frequency of minimum attenuation.

45 It will be understood, therefore, from the above that the expression "low frequency responsive device" in this specification includes an amplifier selective of low frequencies and also an oscillator for generating low frequencies. It may also be 50 mentioned that the term "low frequency" as em-

ployed in this specification refers to frequencies of the order of 200 cycles per second and below.

Although the fundamental circuit described herein and the application thereof as described contains a high pass filter in the feed-back circuit and a low pass filter in the amplifier circuit each of which consists of a single L section made up of a resistance and a capacity, the invention also includes a low frequency responsive device comprising a fundamental circuit in which high 5 pass filter is in the amplifier circuit and the low pass filter in the feed-back circuit. With this latter arrangement there would be a frequency of minimum attenuation as described. The invention will hereinafter be described with reference to the arrangement shown in the drawings, in which the low pass filter is in the amplifier circuit, but it must be appreciated that the invention embodies also the alternative arrangement.

20 In order that the invention may be clearly understood reference is directed to the accompanying drawings which show diagrammatically and by way of example embodiments of the present invention.

25 In the drawings:

Fig. 1 shows diagrammatically one form of what is referred to herein as a fundamental circuit;

Fig. 2 shows a simple form of circuit embodying the fundamental circuit shown in Fig. 1;

Fig. 3 shows a more practical arrangement of circuit than that shown in Fig. 2, more particularly for use as a "tuned" amplifier;

Figs. 3a, 3b, 3c are graphs showing the attenuation curves for the fundamental circuit.

Referring briefly to Fig. 1, it will be observed that the fundamental circuit comprises an input x , an output y , a low pass filter LPF, and a high pass filter HPF, and an amplifying device A.

The high pass circuit which forms a feed-back circuit comprises a condenser C_2 and a resistance R_2 (see Fig. 2) and the low pass filter which forms a part of the amplifying circuit comprises a condenser C_1 and a resistance R_1 (see Fig. 2). The attenuation curves of the two sections of the fundamental circuit together with combined or resultant curves are shown in Figs. 3a, 3b, 3c. In Fig. 3a, the curve marked A is the attenuation curve of C_1R_1 and the curve marked B is the attenuation curve of C_2R_2 whilst the curve C in dash lines is the resultant attenuation curve for both circuits. If the ratio

$$\frac{C_2R_2}{C_1R_1}$$

be chosen correctly, that is to say, in the region of unity (1) the resultant curve has a rounded form with a definite minimum (see Fig. 3a). On the other hand if the ratio

5

$$\frac{C_2 R_2}{C_1 R_1}$$

is too high (Fig. 3b) or too low (Fig. 3c) the 10 resultant attenuation curve has a flattened minimum portion. In Figs. 3b and 3c the individual curves are marked in a manner corresponding to the marking in Fig. 3a.

Considering now Fig. 3a, if the net gain of 15 the amplifier be increased there will obviously come a time when the minimum of the curve reaches or approaches very closely to the level of zero attenuation. At this point the circuit becomes unstable and will start oscillating at 20 the frequency of minimum attenuation of the curve indicated at D. The property is utilised in a low frequency responsive device in the form of an oscillator in accordance with the present invention for generating oscillations of low frequency, for example, for test purposes and it 25 may be mentioned that for all practical purposes there is no particular lower limit to the frequency that may be obtained owing to the absence of inductances in the circuit. The frequency of the oscillations produced is given by 30 the following formula, where f is the "resonant" frequency

35

$$f = \sqrt{\frac{1}{R_1 C_1 \times R_2 C_2}}$$

Therefore by a suitable variation in the values of the resistances and/or the capacities any desired testing frequency may be produced. Frequencies as low as 0.1 cycle per second can be 40 produced with quite convenient values of resistance and capacity.

Considering now the application of the fundamental circuit to a low frequency responsive device in the form of an amplifier for the selection of a particular frequency let it be supposed 45 that the gain of the amplifier is critically adjusted in such a manner that the minimum of the resultant attenuation curve, i. e. the curve C comes close to, but not quite down to, the level 50 of zero attenuation. If this particular frequency be fed into the amplifier it will be amplified to a considerably greater extent than any other frequency. The increase in attenuation due to the high pass and low pass circuits alone on each 55 side of the "resonant" frequency is only about 2 decibels at one half and at twice the "resonant" frequency, but this discrimination can theoretically be increased indefinitely by increasing the gain of the amplifier and so reducing the minimum attenuation to an infinitesimally small 60 value as described without overstepping this point into the region of self oscillation. There are, of course, certain practical limits to this increase in discrimination governed chiefly by the 65 stability of the gain in the amplifier. It seems from theoretical calculations that this discrimination could be increased to 30 or 40 decibels without great difficulty. The "resonant" frequency in this application is of course given by 70 the same formula as for the production of oscillations mentioned above.

Turning now to consider the circuits in rather more detail Fig. 2 shows a simple way in which the fundamental circuit may be embodied in an 75 amplifier but while this circuit arrangement is

convenient from the point of view of explanation of the invention it is not an entirely convenient embodiment as will be explained in a moment. In Fig. 2 the source of voltage is connected between the input terminals I and II and the terminal I is connected directly to the grid electrode of a triode valve V₁. The anode of this valve V₁ is connected through a resistance R₆ to the positive pole of a suitable source of potential and through a condenser C₄ to the input of the fundamental circuit of the kind shown diagrammatically in Fig. 1. The input of the fundamental circuit is connected through a resistance R₇ and a source of grid bias G_{B2} to earth and also through the resistance R₁ of the fundamental 10 circuit to the grid electrode of a second triode valve V₂. Connected between the resistance R₁ and the grid of V₂ is a lead to the condenser C₁ of the fundamental circuit which is in turn connected to earth, the resistance R₁ and the condenser C₁ forming a low pass section of the fundamental circuit.

The cathode of V₂ is connected to the cathode of V₁ and also to earth in the usual manner. The anode of V₂ is connected to a source of potential through the resistance R₈ and through a condenser C₅ to the output O. The anode of V₂ is also connected through the condenser C₂ and the resistances R₂, R₃ to earth. The junction of the resistances R₂, R₃ is connected to the input of the valve V₁. In this way a part of the output potential developed across the resistances R₂ and R₃ namely that developed across the resistance R₃ is fed to the grid of V₁. The amount fed back can be adjusted by varying the value R₃ and for 30 this purpose R₃ may be arranged as an adjustable resistance. Alternatively of course, a simple adjustable potential divider may be used instead of R₂+R₃. The condenser C₂ and the resistances R₂+R₃ in series forming the high pass section 40 of the fundamental circuit.

As was explained above there are certain modifications required to make the above circuit suitable for practical use and Fig. 3 shows the same circuit embodying two modifications which render the arrangement a practical one. The objection to the Fig. 2 circuit is that neither of the input terminals I or II can be connected to earth since this would short circuit the feed-back circuit resistance R₃. It will be understood that 50 there are a number of ways in which Fig. 2 may be modified and that Fig. 3 shows one convenient way.

In Fig. 3 the feed back resistance R₃ is included as a cathode resistance for V₁ thus making it 55 possible to apply the input between the grid of V₁ and earth. The third stage of amplification has been included primarily in order to obtain a phase reversal since feed-back in the opposite phase is required when the resistance R₃ is put in this 60 position. This would be possible with either one stage or three stages but there are several advantages in using three stages. Firstly, the combination R₂ R₃ acts as a potential divider to obtain the correct amount of feed-back and if there 65 is plenty of gain in the amplifier within the feed-back path, then R₃ can be made very small which is a good thing because if R₃ is large it will produce a correspondingly large amount of negative feed-back in the valve V₁ which will reduce the 70 gain of this stage. This is perhaps not a great disadvantage and in fact, might be useful, but if negative feedback is to be used in this stage it would be better to include this outside the positive feedback path, i. e. in the form of another 75

resistance between R_3 and the cathode of V_1 . Another reason for making R_3 small is that a change in its value will not then change the value C_2R_2 substantially. The extra stage of amplification 5 may very well be required in any case to obtain adequate output from a small signal so that from this point of view it is useful.

The additional gain provided in this way has another very definite advantage in that it makes 10 possible the use of a considerable degree of negative feed-back in the amplifier. This would appear to be particularly useful in this case because as is well known, one of the characteristics of negative feedback is that if a large amount of 15 negative feedback is used the net gain of the amplifier depends only on the properties of the feed-back circuit and not on the stage gain of the amplifier. It should therefore be possible to make the effective gain nearly independent of changes 20 of valve voltages and so on, thereby obtaining stable operation of the positive feedback. In the Figure 3 circuit the negative feedback is applied via R_4 and R_5 round the last two stages only. There are many other ways in which it could be 25 employed but the negative feedback must obviously not include either section of the fundamental circuit $R_1 C_1$ and $R_2 C_2$.

The frequency of the oscillator or "tuned" 30 amplifier selective of a particular frequency is very simply varied by altering R_1 and R_2 or C_1 and C_2 in such a way as to maintain the ratio

$$\frac{C_2R_2}{C_1R_1}$$

35 substantially constant and equal approximately to unity (1.0). One very convenient way of effecting this in such a way as to cover a wide frequency range is to make R_1 and R_2 continuously variable in the form of a pair of ganged resistances and C_1 and C_2 variable in steps with a pair of ganged stud switches. As an example of 40 such an amplifier tuned to 50 cycles per second

$$R_1C_1 = R_2C_2 = \frac{1}{314}$$

$$R_1 = R_2 = 0.1 \text{ megohms}$$

$$C_1 = C_2 = 0.0318 \mu F$$

An amplifier of this type could also be given band 50 pass properties by making the ratio

$$\frac{C_2R_2}{C_1R_1}$$

55 considerably larger or smaller than 1.0 as indicated in Fig. 3b and 3c. It will be understood that this form of frequency selective circuit might be wanted instead of one with a single pass frequency in the same way that ordinary tuned circuits are arranged either to pass a single frequency or a band of frequencies.

The selectivity of the fundamental circuit could be improved by employing more than one section in one or each filter, for example, the low pass 60 filter might be composed of two L sections, each consisting of a series resistance and a shunt capacity so as to give a double filter with a greater degree of attenuation above the cut-off frequency than a single section. Similarly, the high 65 pass filter might be composed of two sections each consisting of a series capacity and a shunt resistance. Such an arrangement would lead to greater phase changes in both filters than with a single section for each and would therefore tend 70 to turn the positive feed-back into a negative 75

feed-back at a frequency near to the frequency of minimum attenuation, and it would appear that this fact combined with the greater curvature of the attenuation curves should give distinctly greater selectivity of the device as a whole. 5

One rather obvious point which should be borne in mind when putting this device into practical operation is that it is desirable to arrange the operating conditions for the amplifying valves in such a way that they are working on a part of 10 their characteristic which gives the maximum value for the amplification. The reason for this is that the gain of the amplifier would then not increase with the amplitude of the input or output signal. If this were to occur and the gain of 15 the amplifier had been adjusted so as to be just on the point of self oscillation, a large input signal would increase the gain of the amplifier and this would result in the system actually going into a state of oscillation. Correspondingly, 20 when the circuit is used as an oscillator it would usually be desirable for the amplitude of the oscillation to increase gradually as the feedback is increased beyond the critical value. This would occur if matters were arranged as described, 25 whereas the amplitude of the oscillation would suddenly rise from zero to a large value and in all probability there would be a considerable harmonic content in the output for obvious reasons. 30

What is claimed is:

1. A low frequency responsive device comprising an amplifying device having an amplifier circuit, a feedback path from the output of said amplifying device to the input circuit thereof, and a 35 fundamental circuit for said amplifying device containing only resistance and capacity elements so arranged as to form a high pass section and a low pass section, one of said sections being in the feedback path, and the other of said sections 40 being in said amplifier circuit.

2. A low frequency amplifier, characterised in this, that the said amplifier comprises a fundamental circuit containing no inductances but resistances and capacities so arranged as to form a 45 low pass section and a high pass section, the low pass section being in the amplifier circuit and the high pass section being in a feed back circuit, the net gain of the amplifier being adjusted so that the minimum of the resultant attenuation curve 50 of the two sections of the fundamental circuit comes close to but not quite down to the level of zero attenuation, whereby the fundamental circuit operates in a manner analogous to a tuned circuit responsive to the "resonant" frequency. 55

3. An oscillator for generating low frequency oscillations, characterised in this, that the oscillator comprises a fundamental circuit containing no inductances, but resistances and capacities so arranged as to form a high pass section 60 forming a feed back circuit and a low pass section forming part of the amplifier circuit, the net gain of the amplifier being increased until the attenuation of the fundamental circuit is substantially zero whereby the circuit is rendered 65 unstable and starts to oscillate at the frequency of minimum attenuation.

4. A low frequency responsive device according to claim 1, wherein the low pass section is in the feed back circuit and the high pass section is 70 in the amplifier circuit.

5. A low frequency responsive device according to claim 2, characterised in this, that the low pass section of the fundamental circuit contains a capacity C_1 and a resistance R_1 and the high pass 75

section of the fundamental circuit contains a capacity C_2 and a resistance R_2 , the ratio

$$\frac{C_2 R_2}{C_1 R_1}$$

5 being chosen in the region of unity (1) so that the resultant attenuation curve has a rounded form with a definite maximum.

6. An amplifier according to claim 2, characterised in this, that the discrimination of the fundamental circuit on either side of the "resonant" frequency is increased to a value above that given by the high pass and low pass sections of the fundamental circuit alone.

10 7. A low frequency responsive device, according to claim 1 in which said amplifying device includes a plurality of vacuum valve stages, characterised in this, that the feed back path comprises a resistance (R_3) is included in the cathode circuit of the first valve for the purpose specified, an odd number of stages of amplification being provided in order to obtain the correct phase for the feed back.

15 8. A low frequency responsive device according to claim 1 in which said amplifying device comprises a plurality of stages further comprising a negative feedback circuit for said amplifying device to obtain particularly stable characteristics in the amplifier, arranged around the last two stages of amplification.

20 9. A low frequency responsive device according to claim 1, characterized in this, that the resistances of the fundamental circuit are con-

tinuously variable, and the capacities are variable whereby said fundamental circuit may be adjusted so said device may operate as a low frequency amplifier responsive to any particular frequency or a low frequency oscillation responsive to any particular frequency.

25 10. A low frequency responsive device according to claim 1, in which said low pass section comprises a capacity C_1 and a resistance R_1 and is included in said amplifier circuit, and said high pass section comprises a capacity C_2 and a resistance R_2 and is included in said feedback circuit, the values of the capacities and resistances being such that the ratio

$$\frac{C_2 R_2}{C_1 R_1}$$

30 is appreciably different from unity, whereby said device has a band pass frequency characteristic.

20 11. A low frequency responsive device according to claim 1, wherein said low pass section comprises two portions each including a series resistance and a shunt connected condenser, and said high pass section comprises two portions each including a series condenser and a shunt resistance.

25 12. A low frequency responsive device according to claim 1, characterized in that the resistances of said fundamental circuit are made in the form of variable gauged resistances, and said capacities are made variable in steps by means of gauged stud switches.
